RADIO COMMUNICATION SYSTEM

Robert Winfield Hart, Lynn, Mass., assignor to
 Submarine Signal Company, Boston, Mass., a
 corporation of Maine

Application January 13, 1940, Serial No. 313,713

2 Claims. (CL 177—341)

The present invention relates to a radio transmitting and receiving system and more particularly to an alarm signal system therefor, also called a selective ringing system.

In radio telephone communication systems where it is desired to attract the attention of any one of a plurality of receiving stations from one or more central stations or where it is desired to be able to call any station from any other station, it is necessary to have some form of selective call system. Such a system should make it possible to operate an alarm at any desired one of a group of receiving stations without affecting the alarms at other receiving stations and regardless of static or other interference conditions. The present invention provides an arrangement of this type.

The invention will best be understood from the following description taken in connection with the accompanying drawings in which Fig. 1 is a schematic diagram of an alarm signal transmitting device operating in conjunction with a radio transmitter, and Fig. 2 is a schematic diagram of an alarm-operating receiving device which is used in conjunction with a radio receiver.

In general the present invention contemplates the transmission by the calling station of a series of radio frequency impulses of substantial time length, the several successive impulses being modulated or interrupted at different low audio frequencies. The order in which these impulses are transmitted is different for each station to be called. The transmitted impulses are received at all the receiving stations but serve to operate an alarm only at the station having its receiving apparatus arranged to respond to the particular order of frequencies transmitted.

As shown in Fig. 1, the alarm signal transmitting apparatus comprises a series of sharply tuned vibrating reeds 1, 2, 3 and 4. Each of these reeds is tuned to different low frequencies, for example, 25, 30, 35 and 40 cycles per second, respectively. Vibration of the reeds is maintained by electromagnets 5 to 8, respectively, which are provided with windings 9 to 12. These are connected in parallel to one side of a direct current source through current-limiting resistors 13 to 16. The other ends of the windings 9 to 12 are connected to the respective reeds 1 to 4, the circuit to the other side of the direct current supply being contemplated through contacts 17 to 20, each of which is closed once during each cycle of vibration of the reed to which one of the contacts is attached. The contacts 17 to 20 are shunted by spark-suppressing condensers 21 to 55

24. The reeds are initially set into vibration by means of the cams 25 to 28 all of which are mounted on the shaft 29 which can be rotated by means of the knob 30. The cams in the initial position bear against the studs 31 to 34 mounted on the reeds. The projections on the cams thus tension the reeds in one direction. Further rotation of the cams then permits the reeds to swing back and thereby momentarily to close the contacts 17 to 20, whereby the magnets 5 to 8 will be momentarily energized, attracting the reeds toward them and thereby breaking the contacts 17 to 20. The magnets are therefore again de-energized and the reeds return to the right again, closing the contacts. Vibration of the reeds is thereby continued until stopped by rotation of the cams so that their projections again contact the studs 31 to 34.

20 The rate at which the several reeds vibrate and therefore the rate at which their respective contacts are opened and closed is in each case determined by the natural frequency of the reeds. As above stated, the frequencies of the several reeds are different and are preferably chosen in the 25 low audio frequency range, but other frequencies may be used if desired. Each reed can readily be adjusted to vibrate at precisely the correct frequency by adjustment of the position of the end weights 36 to 39.

30 The contacts 17 to 20 are also each in series with a circuit which includes the operating coil 40 of an electromagnet 41 which operates the transmitter keying relay 42. The contacts 43 of this relay are preferably normally closed and are 35 opened when the magnet 41 is energized. The relay coil 40 has one side connected by the lead 44 to one side of the direct current supply. The other side of the coil 40 is connected by parallel paths to the keys 45 to 48, the other side of each 40 key being connected to one of the reeds and thence through the reed contacts to the second side of the direct current line. Thus when the key 45 is closed, the relay coil 40 will receive 45 momentary energization each time the contact 17 of the reed 1 closes. Contact 43 of the keying relay is therefore opened at the frequency of vibration of the reed 1, for example 25 times a second. The radio transmitter is therefore keyed at this frequency and the resulting radio signal impulse will be interrupted at the same frequency. The length of the impulse is controlled by the time during which the key 45 is depressed. Similarly, impulses of other frequencies can be transmitted by closing any one of the other keys 46, 47 or 48. In practice it will usually be found

desirable to transmit signal impulses of approximately 4 seconds duration. Finally it should be noted that the keying relay 42 must be of the quick operating type so that it is able to respond at the frequencies to which the several reeds are tuned. While the arrangement shown operates to interrupt the radio frequency carrier at the reed frequencies, it will be understood that, if desired, modulation of the carrier may be used instead.

The alarm-operating equipment for the receiving stations is shown schematically in Fig. 2. Alarm signal impulses received by the antenna 50 are passed through the detector 51 and the low frequency amplifier 52 from which they are supplied to the operating coils 53 to 56 of sharply tuned vibrating reed relays 57 to 60. These may be substantially similar to the transmitting reeds shown in Fig. 1 but they must be capable of automatically commencing vibration when energized at the proper frequency. As shown in the drawings the several coils 53 to 56 are connected in series so that all the received signals pass through all of the coils. The vibrating reeds 61 to 64 are, however, sharply tuned so that none will vibrate unless the current passing through its operating coils very closely corresponds to the reed's natural frequency. Each reed connects with one or the other of a pair of parallelly connected contacts 65 to 68, respectively, thereby closing twice in each vibration of the reed a circuit containing the battery 69. Each of the reeds 61 to 64 controls a relay 71 to 74, respectively, having the operating coils 75 to 78, respectively. Relay 71 is provided with two normally open contacts 71A and 71B. Relay 72 is similarly provided with two normally open contacts 72A and 72B and a normally closed contact 72C. Relays 73 and 74 are similar to relay 72 having two normally open and one normally closed contact, namely 73A to 73C and 74A to 74C. In series with the operating coils 75 to 78 of the relays 71 to 73 there are the normally closed contacts 79 to 81, respectively, of thermal time delay relays 82 to 84, respectively, which are provided with operating heaters 85 to 87.

The several relay contacts are arranged in such a way that the relays cannot operate until the contacts of the preceding relay have operated. Operation of the final relay operates the alarm 88 which may be energized by a battery 89. This takes place in the following manner. The relay coil 75 which is connected in series with the contact 79 is energized from the battery 69 by vibration of the reed 61 which closes contacts 65. Energization of coil 75 closes contacts 71A and 71B. Contacts 71A are in series with the normally closed contacts 72C, the coil 75, contacts 79, battery 69 and heater coil 85 of the thermal relay 82. There is thus provided a direct battery connection which maintains the coil 75 energized and the relay 71 in operated condition when the contacts 71A are closed. The relay 71 will, therefore, remain in operative condition even after the reed 61 ceases to vibrate. However, the holding current for the coil 75 must pass through the thermal relay heater coil 85, causing a heating of the thermal elements in the relay 82 and, after a time, opening of the contacts 79. The operating coil 76 of relay 72 is in a similar manner first energized by vibration of the reed 62 which periodically closes contact 66. The coil 76 is, however, not directly connected to the battery through the contact 66 but it is connected in series with the contact 71B of the relay 71.

Vibration of the reed 61, therefore, only effects operation of the relay 72 if at the time the contacts 71B are closed. If this is the case, the coil 76 will be energized by vibration of the reed 62, thereby operating the relay 72 to close contacts 72A and 72B and to open contacts 72C. The opening of contact 72C opens the holding current circuit for coil 75 of relay 71, thereby deenergizing the same and causing relay 71 to assume its normal condition.

The closing of contact 72A closes a holding current circuit which includes normally closed contact 73C and thereby maintains the relay 72 in an operated condition even after the reed 62 ceases to vibrate. The closing of contact 72B prepares the circuit including the operating coil 77 of relay 73 for operation upon the vibration of the reed 63. If this occurs, the operation of relay 73 opens the holding current circuit to relay 72 at 73C, closes its own holding current circuit at 73A and prepares, by closing of contact 73B, the relay 74 for operation by vibration of the reed 64. In a similar manner vibration of the reed 64 by energizing coil 78 of relay 74 interrupts the holding current circuit of relay 73 and closes its own holding current circuit at 74A. The closing of contact 74B serves to close the circuit to the alarm 88. The holding current circuit for coil 78 can be interrupted only by pressing the alarm release key 90. This deenergizes the relay coil 78 and thereby stops the alarm.

From the above it will be evident that the alarm can be operated only if the reeds 61 to 64 are vibrated successively. Since these reeds are tuned to different frequencies, they will operate successively only if signal impulses of the corresponding frequencies are successively received in the proper order. For example, if any other frequency than that corresponding to reed 61 be received first, nothing at all will happen, for none of the relays 71 to 74 can operate unless the preceding relay has been operated. As a further example, if it be supposed that an impulse of frequency corresponding to reed 61 was duly received, thereby operating relay 71, nothing further will happen if the following signal has a frequency other than that of reed 62. If, for example, the following signal had the frequency of reed 63, this reed would vibrate closing contact 67 but the relay coil 77 would not be energized since the contact 72B of relay 72 would still be open. Consequently this signal would have no effect. Moreover, in a short time after the initial operation of reed 61 the thermal relay 82 would operate to open relay 71 so that even though the third signal corresponded in frequency to the reed 62, the alarm still would not be operated. The time of delay prior to the opening of the thermal relay must, of course, be chosen as less than the time required to transmit two successive signal impulses.

Each transmitting and calling station is provided with the low frequency impulse transmitting equipment shown in Fig. 1 and each receiving station is equipped with an alarm system as shown in Fig. 2. Both transmitting and receiving systems contain the same number of tuned reeds of the same frequencies. In the several receiving stations, however, the order in which the frequencies of the reeds is arranged is different for each station. In order to call any particular receiving station it is therefore merely necessary for any one of the transmitting stations to transmit four radio impulses, each of approximately four seconds' duration, consecu-

tively varying in frequency in accordance with the frequency arrangement of the tuned reeds at the receiving station which is being called. Any desired order of frequencies can be used to designate a receiving station except that the same frequency cannot be used successively although it may be used alternately with one other frequency. Thus, although it has been stated that the four consecutive signal impulses transmitted to call a particular receiving station must be of different frequency, it should be noted that they need only be consecutively different in order to provide complete selectivity. Most receiving stations will have their four reeds all tuned differently, but some may have alternate reeds tuned to the same frequency. In this way by providing four differently tuned reeds at each transmitter it is possible to call 108 different receiving stations selectively. By increasing the number of differently tuned reeds in the transmitters to five and increasing the receiving reeds and accompanying relays at the receiving stations to five, it is possible to call selectively any one of 1280 receiving stations. Still more reeds can, of course, be used if necessary.

The present invention not only provides an efficient selective radio alarm system but also one which is not subject to erroneous and false alarms on account of static or other radio interference. This arises out of the use of tuned reeds which can readily be adjusted to require the continuance of the low frequency signal of proper frequency for a period of several seconds before engaging their respective contacts. It is seldom to be expected, therefore, that static or other radio interference will provide impulses of precisely the right frequency for a long enough period of time to actuate any of the receiving reeds with a large enough amplitude to cause them to close their contacts.

Having now described my invention, I claim:

1. An alarm signal receiving system for selective response to a code of a plurality of successive signal impulses of successively different frequencies arranged in a predetermined order comprising a plurality of relay circuits corresponding to the number of signal impulses in said code, each circuit containing a resonant vibratory reed relay tuned to one of the frequencies in said code, second relay means in each of said circuits adapted to be operated by the respective reed relays, contacts in said relay means, a power source, a plurality of time-delay devices and circuit connections between said elements

and between said circuits for maintaining said second relay means closed after said reed relays cease to operate, for subsequently opening each of said second relay means a predetermined time after its first closing and for preventing the operation of any of said second relay means except while the second relay means in the preceding circuit is closed and alarm means in the last of said circuits, whereby the alarm is operated only after receipt of said different frequency impulses in said predetermined order.

2. An alarm signal receiving system for selective response to a code of successive signal impulses of successively different frequencies arranged in a predetermined order comprising a plurality of relay circuits corresponding in number to the number of signal impulses in said code, each circuit including a resonant vibratory reed relay tuned to one of the frequencies in said code and having contacts adapted to be closed by the vibration of the reed upon energization of the relay by a signal of the respective frequency and a locking relay having an operating coil and first and second normally open contacts 20 adapted to be closed when the relay coil is energized and said locking relays in each circuit except the first having third contacts normally closed and adapted to be opened when the relay coil is energized, the several relay circuits being 25 arranged with the tuned reeds in the order of the frequencies of the code to which response is desired, a power source, a plurality of time-delay devices, one for at least all but the last of said relay circuits, said time-delay devices having operating coils and normally closed contacts 30 adapted to be opened a predetermined time interval after the beginning of current flow through them, means connecting said reed-relay contacts, power source and time-delay device contacts of 35 each circuit in series and in each circuit except the first also in series with said second contacts of the holding relay in the next preceding circuit, means connecting said power source, first locking relay contacts, locking relay operating 40 coil and time-delay device operating coil of each circuit together in series and in each circuit except the last also in series with said third contacts of the locking relay in the next following circuit, alarm means in the last of said circuits 45 and means for operating the alarm in response to operation of the locking relay in said last relay circuit.

ROBERT WINFIELD HART.
